US0D1027900S

(12) **United States Design Patent** (10) **Patent No.:** **US D1,027,900 S**
(45) **Date of Patent:** **** May 21, 2024**

(54) **BONE CONDUCTION HEADPHONES**

(71) Applicant: **U-LOVELIFE (SHENZHEN) TECHNOLOGY CO., LTD**, Shenzhen (CN)

(72) Inventors: **Jun Ma**, Shenzhen (CN); **Huixian Tian**, Shenzhen (CN); **Hui Pan**, Shenzhen (CN); **Liu Meng**, Shenzhen (CN)

(73) Assignee: **U-LOVELIFE (SHENZHEN) TECHNOLOGY CO., LTD**, Shenzhen (CN)

(**) Term: **15 Years**

(21) Appl. No.: **29/848,620**

(22) Filed: **Aug. 3, 2022**

(30) **Foreign Application Priority Data**

Mar. 24, 2022 (CN) 202230157900.2

(51) LOC (14) Cl. **14-01**

(52) U.S. Cl.

USPC **D14/205**

FOREIGN PATENT DOCUMENTS

GB 6227076 * 8/2022

Primary Examiner — Paula Allen Greene

(57) **CLAIM**

The ornamental design for a bone conduction headphones, as shown and described.

DESCRIPTION

FIG. 1 is a perspective view of bone conduction headphones showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the bone conduction headphones where the bone conduction headphones is in a configuration of use.

The broken lines in the drawings depict portions of the bone conduction headphones that form no part of the claimed design.

1 Claim, 9 Drawing Sheets
